UNITED STATES PATENT OFFICE.

JOSEPH ELIE THÉODULE JACQUEMIN AND MAURICE PASCHAL CÉLESTIN FRÈRE, OF
BRUSSELS, BELGIUM.

TARGET-PRACTICE DEVICE.

Application filed April 29, 1924, Serial No. 709,928, and in Belgium May 1, 1923.

This invention relates to target practice devices of the kind in which movable elements, such as levers for example are arranged parallelly to each other and adapted 5 to follow the displacements of the aiming line, the said elements cooperating with a recording target and a registering point or needle in such a manner that, at the moment of firing the registering point will be in 10 the same position relative to the recording target that the aiming line is to the centre of the true target, the aiming of the marksman being thus registered by the closure of an electric circuit at the moment of firing, 15 without the issuance of a projectile.

In a device of this kind, it is necessary, on account of the relatively small distance between the movable elements or groups of such elements acting as supporting points 20 for the gun, to amplify the movements of the said supporting points in order to insure that a small error in the aiming, relative to a true target placed at a given distance from the device may be clearly observed on the 25 registering target.

One object of the invention is to provide simple and improved means to secure this result.

Another object of the invention consists 30 in so arranging the cooperating parts or elements of the device that the gun can be manipulated freely by the marksman as in ordinary practice, any interfering action of the device on the gun being avoided.

And a still further object of the invention consists in so establishing the connections 35 between the supporting points of the gun and the registering point or needle that any flexible connection which could be a cause of error in the registration may be avoided.

With these objects in view, the invention 40 essentially consists in the special arrangements and combinations of parts as herein-after fully described and pointed out in the appended claims.

Referring to the annexed drawings which show, as an example one embodiment of the invention:

Fig. 1 is a top view of the device, some 45 parts being shown diagrammatically only by dotted lines corresponding to the central lines of the parts and their connecting points.

Fig. 2 shows a vertical longitudinal section taken on line A—B in Fig. 1.

Fig. 3 shows a vertical transverse section taken on line C—D in Fig. 2 when looking in the direction of the arrows.

The device shown comprises a frame 1 carrying on cross-pieces 2 supporting posts 3 in which two pairs of rails 4 are mounted and on which two carriages 5 and 6 are adapted to roll. Each of said carriages comprises two plates 7 which are connected together by cross-bars 8 and are provided with axles 9 supporting wheels 10 preferably mounted on the said axles by ball-bearings 11 as shown in Fig. 2.

The plates 7 bear inside the carriages, pivots 12 supporting on each plate two pairs of pulleys 13 forming a guiding system for a vertical carriage 14 comprising two rods 15 and 16 which are connected by rods 17. On the upper rod 17 of each vertical carriage is a fork 19 carrying a pulley revolvable about a horizontal axis. Each fork is vertically pivoted to its associated rod 17 by means of a stud 18.

Both pulleys 20 and 21 act as shown in Fig. 2, as supporting means for the gun during the aiming as will be explained later on.

The vertical carriages 14 are balanced by counterweights 22 which, in the example shown, are suspended on cables 23 passing around pulleys 24 which are adapted to rotate on an axle 25 extending between the plates 7. The weights 22 are raised when the vertical carriages are depressed by movement of the gun, and when the gun is raised the weights raise the carriages, maintaining 90 them in contact with the gun. The weight of the counter weights should be such that they will substantially balance the carriages when the gun is resting on the latter, and will therefore raise the carriages when the 95 gun is raised.

A pantograph 34, the rods of which are jointed at 35—36—37—38 as shown diagrammatically in Fig. 3, is connected by a joint 39 to a stud 40 projecting horizontally from 100 the rod 15 of the vertical carriage 14 moving between the guiding pulleys 13 of the horizontally movable fore-carriage 5 (that is to say, the carriage supporting the fore-end of the gun when looking in the direction of 105 the target aimed at). The points 33—39 and 42 of this pantograph will always be on the same straight line on account of the principle of the type of pantograph which is used.

A second pantograph, or correcting pantograph 27, the rods of which are jointed at 28, 29, 30, 31 is pivoted at a fixed point 26 to the frame of the device; another point 32 of this correcting pantograph is connected to the rear vertical carriage moving between the guiding pulleys of the horizontal carriage 6. The points 26-32 and 33 of this pantograph will always be on the same straight line for the same reason as in pantograph 34. One end of the registering pantograph 34 and one end of the correcting pantograph 27 are pivoted together at 33. As a consequence, the pantograph 34 has no fixed point. The rod 41 of the registering pantograph 34 carries, at its end, a needle 42 which moves in front of a registering target 43.

It will appear from the above description that (if the two movable elements of the fore-carriage 5 are supposed to be maintained invariably fixed) the horizontal and vertical movements which are communicated by the gun 51 (acting on the pulley 21) to the movable elements of the rear-carriage 6, will be transmitted to the point 32 of the correcting pantograph 27. The point 33 of this pantograph is consequently displaced proportionally but in an amplified manner and the movements of this point 33, which is common to both pantographs, cause the needle 42 of the pantograph 34 to be displaced in a corresponding manner, the movement of the needle being again amplified.

Conversely, if it is supposed that the group of movable elements of the rear carriage 6 are maintained in a fixed position, all the horizontal and vertical movements which will be communicated by the gun 51 to the pulley 20 of the fore-carriage 5 will be directly transmitted (with a suitable amplification) to the needle 42 of the registering pantograph 34 which is connected by the stud 40 to the movable elements of the fore-carriage 5.

Consequently the gun may be freely manipulated in all the positions which will be given to it by the marksman, as well in the horizontal direction as in the vertical direction, according to whether the groups of horizontally and vertically movable elements are separately displaced or conjointly displaced.

The registering target 43 is mounted on a supporting arm 44 (Fig. 3) vertically pivoted by means of a cross-head 45 supported between screws 46 and is rocked when armature 47 which is mounted on the arm 44 is attracted by an electro-magnet 48; the core of this magnet is fixed to a support 49 which is fixed to the frame 1 and which carries a fork-like support 50 for the screws 46.

An electric connection (not shown) is provided in a well known manner between the gun 51 and the electro-magnet 48 in such a

manner that at the moment of firing, an electric circuit will be closed by the gun, the said circuit including a suitable battery or other electrical source and the electro-magnet 48.

70

In practice the registering target 43 acts only as a supporting element for recording diagrams which are drawn from a paper-roller and are successively displayed in front of the registering target. When the armature 47 is attracted by the electro-magnet 48, the registering target 43 is oscillated between the screws 46 and strikes the point or needle 42 by which the paper is perforated.

75

In the above described construction all the lateral and vertical displacements of the pulleys 20 and 21 acting as supporting means for the gun, are transmitted to the registering pantograph 34, but the displacements in the same direction of the two points 33 and 39 by which the said pantograph is acted upon impart to the point or needle 42 oppositely directed movements. As a result, in the case of a good aim in an inclined direction, the opposite movements of the point or needle will be balanced through the action of the "correcting pantograph" 27 by which the second point 33 of the pantograph 34 is acted upon, the said action bringing the point again in front of the centre of the registering target 43. On the other hand the action of the "correcting pantograph" 27, pivoted to the fixed point 26, compensates the fact that the multiplying action varies according to the one or the other of points 33-39 of the registering pantograph which is acted upon and also the fact that in a correct inclined aim, the displacement of the fore supporting point 20 of the gun is in a given relation to the displacement of the rear supporting point 21.

80

If it is supposed that the distance between the two parallel vertical planes in which the supporting points 20 and 21 for the gun are displaced during the aiming be represented by d and the distance between the vertical plane containing the target (not shown) and the fore supporting point 20 by D , any displacement in one or the other direction of the rear supporting point 21 will be multiplied on the target by $\frac{D}{d}$ and any displacement of the fore-supporting point 20 by

85

90

95

100

105

110

115

120

125

130

$$\frac{D+d}{d}$$

On the other hand, if it is supposed, by way of example, that the indications on the recording target 43 must be to the deviations on the target properly so called (not shown) in the relation of 1 to 10 and finally that the fore-supporting point 20 is connected to the registering pantograph at 39 and the rear-supporting point 21 at 32 of the correct-

125

130

ing pantograph as above described, it will be observed:

(a) That the registering pantograph 34 for a displacement x of the supporting point 20, must produce at the point or needle 42 a displacement corresponding to

$$\frac{D+d}{10d} X.$$

This condition will be satisfied by calculating the dimensions of the pantograph in such a manner that the relation of the distance a between the points 33 and 38 to the distance b between the points 33 and 35 will correspond to

$$\frac{a}{b} = \frac{D+d}{10d}$$

(b) That when the registering pantograph 34 is acted upon at 35, this action will reverse the displacement of the point or needle 42 but will only produce an amplification in the following relation, if c is supposed to be the distance between the points 35 and 38.

$$\frac{c}{b} = \frac{a-b}{b} = \frac{D+d-10d}{10d} = \frac{D-9d}{10d}$$

(c) That the correcting pantograph 27 must secure such an amplifying action that for a displacement

$$X \frac{D+d}{D}$$

of the supporting point 21, in the same direction as the displacement x of the supporting point 20, the point or needle 42 will be brought again to its initial position which was occupied before the two displacements which are produced first at 20 and then at 21. This amplifying action will be secured by giving to the relation of the distance f between the points 28 and 33 to the distance g (Fig. 3) between the points 28 and 29 the following value:

$$X \frac{D+d}{D} \left(\frac{f}{g} \right) \left(\frac{D-9d}{10d} \right) = X \frac{D+d}{10d}$$

and consequently

$$\frac{f}{g} = \frac{D}{D-9d}$$

The above relations will permit in each case the determination of the numerical proportions of both pantographs. The operation of the device may be summed up as follows:

The marksman places his gun upon the pulleys 20 and 21 and moves the gun, sighting at the true target, into the position in which he thinks it to be aimed at the center of said target. Horizontal movements of the gun cause the carriages 5 and 6 to move horizontally on their rails 4. The said car-

riages, being movable entirely independently of one another, and offering very little resistance because of the ball bearings 11, and the forks in which pulleys 20 and 21 are mounted being pivoted on bars 17, the gun can be freely manipulated.

The horizontal movements of the carriages 5 and 6 impart corresponding movements to the pantographs. If the rear-carriage 6 remains stationary the point 33 remains stationary, and horizontal movements of the fore-carriage will cause the recording pantograph 34 to move with the point 33 as a base. For example, suppose the gun to be aimed to the left of the center of the true target in which case pin 42 would stand to the left of the vertical diameter of the recording target. If the rear carriage is to remain stationary, in order to aim the gun at the center of the true target the forward end of the gun would have to be moved to the right, thereby moving the fore-carriage to the right. It can be seen from Fig. 3 that movement of the fore-carriage to the right will cause pin 40 and its connection 39 with pantograph 34 to move to the right. The point 33 being fixed it can easily be seen that such movement of point 39 will move pin 42 to the right. In other words as the forward end of the gun is swung to aim the gun at the vertical diameter of the true target the pin 42 will be moved correspondingly toward the vertical diameter of the recording target.

On the other hand suppose the gun to be aimed again to the left of the vertical diameter of the true target, and then moved into correct aim by keeping the fore-carriage 5 stationary and moving the rear carriage 6 to the left. In this case the point 39 remains stationary. It can easily be seen from Fig. 3 that movement of point 32 to the left will cause a corresponding movement of point 33 to the left, which will cause pin 42 to move to the right, point 39 being stationary.

In actual practice neither of the above two methods takes place because the gun is swung about the shoulder of the marksman as a center. In this case it is obvious that both carriages will be moved at the same time and in the same direction, and that the fore-carriage compensates for the movement of the rear-carriage by moving slightly more than would be necessary if the gun were swung about the rear carriage as a center.

The action of the pantographs upon movement of the gun in a vertical plane is entirely similar to its action upon horizontal movement of the gun and it will therefore not be necessary to describe this action in detail. When the gun is depressed the vertical carriages 14 are moved down, and when the gun is raised the counter weights cause the carriages to rise and maintain their pulleys 20 and 21 in contact with the gun. The

vertical carriages move entirely independently of one another.

The apparatus as above described, independent of its simplicity, has the great advantage of dispensing with the use of any stepped part combined with the gun, or of steps formed on the gun itself, as was the case in previously used devices of this kind in which the two parallel groups of supporting elements for the gun were constituted by oscillating levers, the necessary difference in the level of both supporting points 20 and 21 being obtained in the present case by the fact that the rear-supporting point (pulley 21) for the gun is normally at a lower level than the fore-supporting point (pulley 20) as shown in Fig. 2.

What we claim is:

1. In a target practice device, in combination two movable supporting elements, the said supporting elements being arranged in vertical parallel planes and adapted to follow the movements of a freely manipulated gun during the aiming of a marksman, a registering pantograph acted upon by the said supporting elements at two movable points, means for recording the movements of the said pantograph and a correcting device, the said correcting device being inserted between one of the supporting elements and the movable point of the pantograph which is acted upon by the said supporting element.

2. In a target practice device in combination two movable supporting elements, the said supporting elements being arranged in vertical parallel planes and adapted to follow the movements of a freely manipulated gun during the aiming of a marksman a registering pantograph acted upon by the said supporting elements at two movable points, means for recording the movements of the said pantograph and a correcting pantograph inserted between one of the supporting elements and the movable point of the registering pantograph which is acted upon by the said supporting elements.

3. In a target practice device, in combination two groups of movable supporting elements, comprising vertically movable supporting members the said groups of elements being arranged in vertical parallel planes and adapted to follow the movements of a freely manipulated gun during the aiming of a marksman, a registering target fixed relative to the gun, a movable registering point or needle cooperating with the said fixed target, a registering pantograph acted upon by one of the groups of supporting elements at a movable point and carrying the registering point or needle, a correcting pantograph acted upon by the second group of supporting elements and a jointed connection between both pantographs where-

by the registering pantograph is acted upon by the correcting pantograph at a second movable point.

4. In a target practice device, in combination a supporting frame, two carriages adapted to be displaced horizontally on the said frame in parallel vertical planes, vertically movable supporting members mounted in the said carriages, whereby a freely manipulated gun may be supported by the said members during the aiming of a marksman, a registering target fixed relative to the gun, a movable registering point or needle cooperating with the said fixed target, amplifying means connecting the vertically movable supporting member of one of the two carriages to the movable point or needle and a correcting device connecting the vertically movable supporting member of the second carriage to the amplifying means whereby the difference of action of both supporting members on the amplifying means is compensated.

5. In a target practice device, in combination a supporting frame, two carriages adapted to be displaced horizontally on the said frame in parallel vertical planes, vertically movable gun-supporting members mounted in the said carriages, a registering target fixed relative to the gun, a movable registering point or needle cooperating with the said fixed target, a registering pantograph carrying the said registering point or needle the said pantograph being acted upon by one of the vertically movable gun supporting members and a correcting pantograph acted upon by the second vertically movable gun-supporting member, the said correcting pantograph being attached to the frame at a fixed point and being connected to the registering pantograph.

6. In a target practice device, in combination a supporting frame, rails mounted on the said frame, two carriages moving parallelly to each other on the said rails, vertically movable gun-supporting members mounted in the said carriages, a registering target fixed relative to the gun, a movable registering point or needle cooperating with the said fixed target, a registering pantograph carrying the said registering point or needle, the said pantograph being mounted in a vertical plane between the two carriages and being acted upon by one of the vertically movable gun-supporting members, a correcting pantograph acted upon by the second vertically movable gun supporting member in a plane parallel to the plane of the registering pantograph, and a connection between the two pantographs.

In testimony whereof we have affixed our signatures.

JOSEPH ELIE THÉODOLE JACQUEMIN.
MAURICE PASCHAL CÉLESTIN FRÈRE.
